INTER-OUTER TELEPHONE SYSTEM

Richard Varley, St. George, N. Y., assignor to
 Inter-Outer Telephone Corporation, Dover,
 Del., a corporation of Delaware

Application August 21, 1935, Serial No. 37,104

29 Claims. (Cl. 179—1)

This invention relates to improvements in systems of telephonic communication and has special reference to acoustically-coupled inter-outer telephone systems of the general type set forth in my copending application Serial No. 733,824, filed July 5, 1934.

One of the objects of my present invention is to provide such an acoustically-coupled inter-outer telephone system, in which a public telephone system may be effectively and efficiently connected in acoustical relation to an entirely separate and electrically independent private inter-office telephone system, without in any way interfering with or modifying the normal operation of the public telephone system, while enabling any branch station of the inter-office system to fully utilize the facilities and service of the public telephone system.

Another object of my invention is to simplify and improve the circuit connections and operation of such an acoustically-coupled inter-outer telephone system, and to extend the use and benefits of the public telephone system to a privately owned and operated inter-office telephone system, while at the same time providing the inter-outer system with improved features of operation and control which are now unavailable in public telephone systems.

A further object of my invention is to provide improved facilities for readily effecting an efficient acoustical coupling between the outer public telephone system and the inter-office system, and, without disturbing or affecting the property of the public telephone system, to utilize the subscriber's public telephone set in such a way that the mere act of picking up the French telephone instrument from its supporting base will perform certain novel and useful functions which are advantageous and desirable to the telephone user, and will also initiate and expedite the operation of certain component parts of the inter-office system, whereby a prompt and efficiently operative acoustical connection may be established between the outer and the inter-office systems.

These and other objects of my invention, and features thereof by means of which they are accomplished, will become apparent from the following description of my invention, as illustrated in the accompanying drawings, in which—

Fig. 1 is a diagrammatical view of a simple inter-outer telephone system embodying my invention;

Fig. 2 is a view, partially in side elevation and partially in section, of a portion of an acoustical coupling device employed in my invention;

Fig. 3 is a fragmentary view, partially in plan and partially in section, of a portion of the coupling device shown in Figure 2 and taken along the section line III—III thereof;

Fig. 4 is a diagrammatic view of a modified and improved telephone system embodying my invention; and

Fig. 5 is a diagrammatic view illustrating a further modification of certain features of my invention.

Referring to the drawings, and particularly to Fig. 1 thereof, one form of my improved inter-outer telephone system is illustrated diagrammatically as embodying a simple inter-office telephone system so arranged that any branch station is capable of talking with the main or operator's station or, through the agency of an acoustical coupling device between the inter-office system and the usual subscriber's telephone of a public telephone system, is enabled to communicate with any outside party having a subscriber's telephone.

In accordance with this form of my invention, provision is made for automatically operating a signal and a timing device and also supplying energy to an electronic amplifier associated with the receiving circuit of the inter-office system as soon as the public telephone instrument is picked up by the operator in answering a call.

Another feature of the invention is the automatic setting up of independently operable and controllable receiving and transmitting circuits in the inter-office system as soon as the receiver at the branch station is picked up for use.

A further feature of the invention resides in providing an acoustical coupling device with which the French telephone instrument of the public telephone system is placed in acoustical relation for inter-outer communication with control means which is so located as to necessitate its operation by the operator before a complete and efficient acoustical coupling can be effected, and which operates in conjunction with auxiliary circuits and devices to prepare for a subsequent and automatic signal to the operator when the telephone conversation has terminated and the called party has hung up his receiver. The operator being thus warned, restores the telephone instrument to its cradle and cuts off the power from the electric amplifier and the first-mentioned signal and timing device.

To accomplish these ends, my invention comprises a main or operator's station O and a plurality of branch stations A and B, which stations may be located at separate points, as in different

rooms of an office building, some of the walls W of which are illustrated in cross-section. Interconnecting the operator's station with the several branch stations is a suitable signal system S, whereby the operator may signal to any branch station. For convenience under certain circumstances, a phonograph P is provided in a separate room adjacent the operator's station in order to permit of recording messages from the outside system, if so desired.

At the operator's station O is located the usual subscriber's desk-type of dial telephone set T having a French-style telephone instrument F constituting a part of the public telephone system. Also disposed adjacent thereto is an acoustical coupling and control device C by means of which the electrically independent outer and inter telephone systems may be connected acoustically and their operation controlled, in accordance with my invention.

The subscriber's telephone set T is provided as usual with a base 2, a dial-operating mechanism 4 and a cradle 6 upon which the French-style telephone instrument F rests when not in use. The instrument F is of well-known construction and embodies a receiver 8 and a transmitter 10 disposed in fixed spaced relation at the respective ends of a hand grip 12.

In order to provide a signal or warning to the operator at such times as telephone instrument F is in use and out of its cradle, the base 2 is positioned upon a movable or floating platform 14 of a sub-base 16, which platform rests upon a plurality of supporting springs 18 carried within the sub-base member. A stationary spring contact 20 is fixedly mounted upon an insulating block 22 secured to the sub-base 16 and in cooperative relation with said spring contact is another spring contact 24 which is mounted on an insulating block 26 secured to the underside of the floating platform 14.

When the telephone instrument F rests in its cradle 6, the weight of the entire telephone set T is sufficient to depress the springs 18 and hold the spring contacts 20 and 24 out of engagement. But when the telephone instrument F is moved from its cradle for use, the weight of the base 2 is insufficient to hold down the platform and the springs 18 raise the platform and telephone base 2, while at the same time bringing the movable spring contact 24 into cooperative engagement with the contact 20. An electrical connection is thereby established from the source of power, marked Power, through power supply wire 30, spring contacts 24 and 20, conductor 34 and thence through a visible or audible signal device 36, such as a lamp or buzzer, which by means of conductors 38 and 39 is connected to the other supply wire 40 from the source of power.

It is sometimes desirable and convenient for the telephone user, particularly when calling a long distance station, to be kept informed as to the length of time of his call, and for this purpose, a timing device 42 is employed which is connected in parallel with the signal device 36 by means of conductors 34 and 46. This timing device conveniently comprises an electric-clock mechanism of the usual type and preferably embodies an alternating current self-starting synchronous motor which rotates an indicator needle 48 in the usual manner. Thus, the operator is visibly and progressively informed as to the length of time of long distance calls. Of course, the signal device and the timing device are main-

tained in operation until the telephone instrument F is restored to its cradle.

The acoustical coupling and control device C is located adjacent the public telephone set T so that the French telephone instrument F may be temporarily hung or placed in acoustical operative relation with the coupling device C. This coupling device C comprises a box-like casing or cabinet 50, parts of which are shown more in detail in Figs. 2 and 3, to which reference is made. This cabinet is provided with an inclined front panel 52 having suitably spaced openings 54 and 56 which are spaced in vertical relation so as to register with the receiver 8 and transmitter 10 of the French phone F when placed in acoustical operative position over said openings and supported in position by an outwardly extending semi-circular supporting flange member 58 which is suitably secured to the front inclined panel 52.

In order to pick up the sound emanating from the receiver 8 of the French telephone F, there is mounted within the cabinet 50 immediately back of the opening 54 and in registry therewith, a microphone 60 which is preferably of the well-known two-button type, although any other suitable type of microphone may be employed. Adjacent the inner end of the panel opening 56 and in registry therewith is mounted a loud speaker 62 of any suitable and well-known construction.

Intermediate the openings 54 and 56 in the panel 52 is an outwardly projecting member 64 suitably attached to the panel proper, and slidably positioned therein is a switch actuating rod 66 having at its outer end a handle or head 68. The inner end of said rod is connected to a switch mechanism 70 which may be of any well-known construction and preferably constitutes a four-pole double-throw snap switch shown in outline in Fig. 3, the operating lever 72 of which is pivotally connected at 74 to the inner end of the actuating rod 66.

Without describing in detail the construction of the snap switch, it will be understood that this type of switch embodies a spring which rapidly throws or snaps the movable contact members into or out of electrical engagement when the operating lever is moved past its dead-center position. Such type of switch not only accomplishes a rapid make-and-break of the electric circuits associated therewith, but, when used in conjunction with the push rod 66, serves to accentuate or hold it in either its inner or outer position, thus requiring a definite push or pull by the operator to effect the operation of the switch associated therewith.

In the schematic diagram of Fig. 1, the control switch 70 is merely shown diagrammatically and comprises a plurality of spring contacts 76, 78, 80 and 82 which are mounted in an insulating block 84 and out of contact one with the other, although a button 86 of insulating material is fixedly mounted on the spring contact 78 and is in physical engagement with the spring contact 80. However, when the actuating rod 66 is pushed inwardly by the operator, the inner end 88 thereof, which in Fig. 1 comprises insulating material, presses against the spring contact 76 and brings the pairs of contacts 76 and 78 and also contacts 80 and 82 into electrical engagement, as will be understood.

The cabinet 50 also contains an electronic sound amplifier 90 of conventional construction including vacuum tubes of the amplifying and rectifying type, choke coils, transformers, condensers and other elements commonly employed

in the construction of such devices. A suitable amplifier is typified by the RCA Victor Portable Sound Amplifier-Type P. G.-63 or the Universal Amplifier Assembly (6 watts) may be employed. 5 While the particular amplifiers mentioned are adapted to be connected to an alternating current source of power, my invention may be carried out with any type of amplifier, such, for example, as those which are connected to a direct current source of power, or those which are operated on batteries. All such amplifiers, regardless of their type, are provided with means for regulating or adjusting the degree of amplification. This is a desirable adjunct in my 10 system, but since it is conventional with all types of amplifiers, it is typified in the drawings only by a simple adjusting knob 98.

The cabinet 50 also contains a change-over switch 92 for shifting certain circuit connections 20 of the system in accordance with certain aspects of my invention. This change-over switch 92 may conveniently take the form of a four-pole, double-throw switch having a plurality of contact arms 94, 96, 98 and 100 which are pivotally 25 mounted at one end and pivotally attached to an interconnecting insulating bar 102, so that they may be moved in unison. Each of the contact arms above referred to is adapted to occupy two operative positions to cooperate with a plurality 30 of stationary contacts 104, 106, 108, 110, 112, 114, 116 and 118. In the operative position shown in Fig. 1, contact arm 94 cooperates with contact 104, contact arm 96 with contact 108, contact arm 98 with contact 112, and contact 35 arm 100 with contact 116. In the other operative position, contact arm 94 cooperates with contact 106, contact arm 96 with contact 110, contact arm 98 with contact 114, and contact arm 100 with contact 118.

40 For convenience in operating the change-over switch 92, the interconnecting bar 102 is provided with a handle 119 which projects through a slot in one of the side walls of the cabinet 50, where it is accessible to the operator for manipulation.

Also within the cabinet 50 are conveniently located auxiliary pieces of apparatus, such as 50 buzzer 120, electromagnetically-operated switch 124, batteries 126 and 128 and certain necessary circuit connections for my system.

The branch stations A and B are alike and for illustrative purposes each embodies a wall-type telephone extension, although any type of telephone may be used. As shown, each comprises a casing 130 within which is disposed a transmitter 132 and an ear type receiver 134. The receiver 134 is normally hung, when out of use, on the hooked end 136 of a hook lever 138 which is pivotally mounted at 140, and the 55 weight of the receiver is sufficient to hold the hook lever in its downward position against a stop 142 in opposition to the action of a coil spring 144, which raises the hook lever when the receiver has been removed therefrom. Immediately 60 above an operating finger 146 of insulating material forming a part of the hook lever 138 is a control switch 139 having a plurality of spring contacts 150, 152, 154, 156 and 158 which are mounted in spaced relation in a block 160 65 of insulating material in such manner that none of the spring contacts is in electrical engagement, as shown at station A. The spring contact 154 is provided with an extended end portion 162 which is normally engaged by an insulating button 164 secured to the lower spring 70

75 contact 158. When the receiver 134 is removed from its hook lever 138, the finger 146 effects an electrical engagement between the spring contacts 150 and 152, and at the same time, through the insulating button 164, spring contact 154 is raised and an electrical connection effected between the spring contacts 154, 156 and 158, as shown at station B.

For the purpose of enabling the operator to call any of the branch stations, a suitable signal 10 or buzzer system S is provided and, as shown, includes a battery 168 to which is connected a push-button 170 adjacent the operator's station and a plurality of buzzers 174, respectively located at branch stations A and B and adapted 15 to be energized through the operator's push button 170, so that through an agreed-upon code, either one station or the other may be rung or called. Of course any type of signal system may 20 be used.

The phonograph P is of a type generally known 25 as a dictating machine and is located in a separate room or sound-proof compartment adjacent the operator's station O. Without describing the phonograph in detail, it will be understood that broadly it includes a driving motor 180 which serves to rotate a mandrel 182 upon which a wax recording cylinder 184 may be inserted in the usual manner. A sound reproducer 186 engages the recording cylinder and is fed lengthwise 30 thereof as the cylinder rotates and, in so doing, reproduces upon the cylinder the vocal sounds which are transmitted through a flexible speaking tube 188 having a mouthpiece 190 in acoustical operative relation with the open side of a 35 loud-speaker 192 of conventional construction, which transmits into speech the varying electrical waves received by it over a suitable electric circuit.

Closely adjacent and in acoustical operative 40 relation with the other side of the loud-speaker 192 and for the purpose of picking up sound waves produced thereby is a microphone 194 preferably of the one-button type, although any suitable microphone may be used, and this microphone functions to pick up and transmit the sound waves or speech received thereby into electrical waves over a suitable electric circuit. 45

The operation of the phonograph P may be 50 remotely controlled by the main station operator through the agency of the usual Bowden wire 196 in a well-known manner by means of which the usual clutch operating mechanism (not shown) of the phonograph may be operated by depressing the operating knob 198, as will be understood from 55 common practice.

Having set forth the general construction and 60 operation of several parts of the apparatus employed in my system, and assuming the receivers 134 at both stations A and B to be hung upon 65 their respective hook levers, the operation and circuit connections of the system will be described and my invention more fully explained.

Assuming the French-style telephone instrument F to be resting in its cradle 6 and that a 70 call is received on the subscriber's telephone set T, the operator picks up the instrument F and determines that the party calling desires to speak with someone at branch station A. The operation is as follows:

Upon removing the telephone instrument F 75 from its cradle 6, the decrease in weight of the telephone set T is such as to permit the springs 18 to raise the floating platform 14 with the telephone stand 2 thereon sufficiently to cause the 75

engagement of spring contacts 20 and 24, and the consequent operation of the visible or audible signal 36 and also of the timing device 42 through the electrical circuit previously described. The 5 operation of the visible or audible signal 36 serves to warn the operator that the telephone instrument F is out of its cradle and the timing device 42 indicates the duration of time of the call.

In addition to effecting the operation of the 10 signal device 36 and the timing device 42, the cooperative engagement of the contacts 20 and 24 also performs another important function. It immediately connects the electronic amplifier 90 to the source of power so as to promptly initiate 15 the warming-up period thereof in order that it may be more quickly ready for service. This is accomplished through a circuit across the source of power which includes conductor 30, contacts 24 and 20, conductor 34 and conductor 197 to one 20 of the terminals 199 of the amplifier 90 and from the other terminal thereof through conductor 40 to the source of power.

As the operator answers the outside call and proceeds to locate the party desired, the amplifier, which has been connected to the source of power, gradually becomes heated to operative 25 condition and is in readiness for use.

This feature of energizing the amplifier when the French telephone instrument is removed from 30 its cradle, is also of special importance when I employ an amplifier of the battery-operated type, such as are now available, and as shown in connection with the modification set forth in Figure 5 of the drawings.

35 The operator having determined, for instance, that a party at branch station A is being called, signals station A, as by a single ring or buzz, through the agency of the push-button 170. When the party at branch station A removes the 40 receiver 134 from the hook lever 138, the spring 144 raises said lever and, by so doing, effects the electrical engagement of the spring contacts 150, 152, 154, 156 and 158 in the manner previously described. Thus, the one-way two-wire transmitting circuit from the transmitter 132 at branch station A to the loud-speaker 62 at the operator's station O is completed and rendered operative 45 through a circuit from one side of the battery 126 through conductor 200, loud-speaker 62, conductor 202, conductor 204, transmitter 132, conductor 206, spring contacts 154 and 156, conductor 208 and conductor 210 to the other side of the battery 126. The party called is thus able to speak to the operator who receives the message 50 through the loud-speaker 62.

In the meantime, the amplifier 90 has been heated up and becomes operative to intensify any electrical waves set up in response to speech in the microphone 60 and transmitted to the amplifier through its input circuit 216. The output circuit of the amplifier 90 is thus rendered operative and includes conductor 218, contact arm 94 and contact 104 of change-over switch 92, conductor 220, conductor 222, spring contacts 150 55 and 152 of control switch 139, receiver 134 at branch station A, conductor 224, conductor 226, contact 108 and contact arm 96 of the change-over switch 92 and conductor 228 to the other output terminal of the amplifier.

70 In this way, the receiving circuit from the microphone 60 through the amplifier 90 and to the receiver 134 of branch station A is placed in condition for operation so that the operator may speak into the microphone 60 and advise the

party called at branch station A that he has a call from the outside public telephone system.

It is pointed out that the operation of the system up to this point is typical of the manner of operation of my system when used for inter-office communication between any branch station and the main or operator's station. 5

Before proceeding with a description of the acoustical connection between the outer and the inter-telephone systems, an important control or 10 signal feature of my invention should be understood. This involves an audible signal to the operator, after the party at branch station A has concluded his conversation and has hung up his receiver 134. In order to understand this 15 feature, it is necessary to revert to the time when the receiver 134 at branch station A was first removed from its hook lever 138, since a part of the circuits of this control or signal feature is established at that time, inasmuch as the 20 spring contacts 156 and 158 are then brought into engagement. This engagement completes a circuit from battery 126 through electromagnet 230 of the electromagnetically-operated switch 124, and thence through conductors 232 and 234, 25 spring contacts 158 and 156 of control switch 139, conductors 208 and 210 to the other side of the battery. The completion of this circuit energizes the electromagnet 230 which draws its armature 236 against the action of a spring 238 to 30 separate switch contacts 240, one of which is mounted on the armature 236, to thereby open an auxiliary circuit in which the buzzer 120 is adapted to be connected. Under these conditions, the buzzer 120 is inoperative. 35

As soon as the party at station A is ready to receive the outside call, the operator depresses the actuating rod 66, thereby bringing contacts 76 and 78 of the control switch 70 into engagement, as already explained. This places energy 40 from battery 126 on the stationary contact 240 of the switch 124 through conductors 242 and 244 and the intervening contacts 76 and 78. The movable contact 240 on the armature switch arm 236 is already connected to the battery 126 through the armature switch arm 236, buzzer 120 and conductor 245. 45

However, the buzzer 120 is still inoperative by reason of the fact that the electro-magnetically operated switch 124 is in open position because 50 of the energization of its electromagnet 230, as already explained. While the buzzer 120 is not now operative, the necessary connections have been established so that, as soon as the party at branch station A hangs up his receiver 134, the 55 electromagnet 230 will become de-energized and the armature switch arm 236 actuated by the spring 238 to close the contacts 240. Thus, the buzzer 120 will be connected across the battery 126 and becomes operative to warn the operator that the conversation has been terminated and that the French telephone instrument should be restored to its cradle.

To continue with the operation of the system, the operator, having depressed the actuating rod 66 and actuated the control switch 70, places the French telephone instrument F in the position shown in Figs. 1 and 2, with the receiver 8 thereof of adjacent and in acoustical relation with the microphone 60 of the coupling device C and the 70 transmitter 10 thereof in acoustical relation with the loud speaker 62 of the coupling device. With the telephone instrument F so placed, it is supported by the semi-circular flange 58 over which the receiver 8 is hung. The hand grip 12 of 75

the instrument rests against or is positioned adjacent the actuating knob or button 68 of the actuating rod 66, which has previously been pushed in by the operator to operate the control switch 70. The actuating rod is so positioned that the telephone instrument F can not be placed in complete acoustical relation with the coupling device C until the actuating rod is depressed and the control switch 70 closed.

10 An acoustical coupling between the subscriber's public telephone system and the inter-office system having thus been effected, without electrically interconnecting the systems or interfering in any way with the normal operation of the 15 outside system, the conversation proceeds in a normal manner, during which the outside call is transmitted through the receiver 8 of the telephone instrument F and through the microphone 60 and electronic amplifier 90 of the coupling device C and thence through the two-wire one-way receiving circuit which includes the receiver 134 at branch station A. On the other hand, the conversation of the party at branch station A is transmitted to the outside calling party 25 through the transmitter 132 of branch station A and thence through an independently operable two-wire one-way transmitting circuit, which includes the loudspeaker 62, by means of which the message is delivered acoustically to the usual 30 transmitter 10 of the French telephone instrument. Of course, by utilizing the adjusting knob 90^a, the operation of the amplifier 90 may be regulated as desired.

Having completed the conversation, the party 35 at branch station A hangs up his receiver 134, thus disengaging all of the spring contacts of control switch 139 within the telephone set at station A and interrupting or disconnecting both the transmitting and the receiving circuits, as 40 well as the circuit through the electromagnet 230. Thereupon, the armature 236 thereof is moved by the spring 238 to close the contacts 240 and energize the buzzer 120, thus signalling the operator that the conversation has been completed and that it is necessary to restore the 45 French telephone instrument F to its normal position upon the cradle 6.

In removing the telephone instrument F from the acoustical coupling device C the operator 50 also grasps the knob or button 68 of the actuating rod 66 and pulls it into its outer position, at which time the associated control switch 70 which is preferably of the snap switch type, operates to break the circuit of buzzer 120 by disengaging 55 spring contacts 76 and 78.

Of course, if the operator should neglect to pull out the actuating rod 66, the buzzer 120 would 60 continue to operate until this is done. The operator then replaces the French telephone instrument F upon its cradle, at which time the added weight of the instrument depresses the floating platform 14 and thereby disengages the spring contacts 20 and 24 to cut off the supply of electrical energy to the amplifier 90, signal device 65 36, and timing device 42. The entire inter-outer system is thus restored to normal conditions and is ready for subsequent use.

As an adjunct to the system hereinbefore described, I have provided the sound recording device 70 or phonograph P already set forth, which may be utilized for the purpose of making a record of any incoming message should it be found desirable to do so, while still permitting the party at the branch station A to hear the incoming 75 message and continue his conversation.

Assuming, for example, the conversation between an outside calling station and a party at branch station A to be in progress and the circuit connections being as heretofore set forth, should it become desirable to record any message from the outside party, the operator has only to close switch 250, which may be conveniently arranged to be operated from outside of the cabinet 50, to thereby connect the motor 180 of the phonograph to the source of power through conductors 252 and 254.

Before attempting to record an incoming message, the operator actuates the change-over switch 92 by means of its handle 119 to its other or "recording" position in which the contact arms 94, 96, 98 and 100 are moved into positions to engage the contacts 106, 110, 114 and 118.

In this position of the change-over switch 92, the receiving circuit from the amplifier 90 is shifted from the receiver 134 of branch station A to the loud-speaker 192 of the phonograph P, while, at the same time, the auxiliary pick-up microphone 194 positioned adjacent the loud speaker 192 is connected through battery 128 and power control switch 70, to the receiver 134 at branch station A.

More specifically, the movement of the change-over switch 92 into its other or "recording" position establishes a circuit from the output side of the amplifier 90 through conductor 218, switch arm 94, contact 106, conductor 256 to the loud speaker 192 of the phonograph P and thence through conductor 258, contact 110, contact arm 96 and conductor 228 to the amplifier. Thus, the receiving circuit is switched from station A directly to the phonograph loud speaker 192.

At the same time, a circuit is established from one side of the battery 128 through conductor 260, spring contacts 80 and 82 of the control switch 70, conductor 262, contact arm 98 and contact 114 of the change-over switch 92, conductor 264, conductor 226, conductor 224, receiver 134, spring contacts 152 and 150 of control switch 139, conductor 222, conductor 220, conductor 266, contact 118 and contact arm 100 of change-over switch 92, conductor 268, microphone 194 associated with the phonograph P, and conductor 270 to the other side of the battery.

The circuit just recited, including the battery 50 128, the pick-up microphone 194 and the receiver 134 of branch station A, serves to acoustically receive a message from the loud speaker 192 of the phonograph P and transmit it to the receiver of branch station A so that the party 55 talking thereon will be able to listen to the message from the outside system which is being recorded by the phonograph P. It will be noted that during the recording of outside messages in the manner just described, the receiving circuit is transferred to the loud-speaker of the phonograph, but is still independently operable from the transmitting circuit.

Having set up the circuits just described for the purpose of recording outside messages, the 65 actual reproduction thereof by the phonograph P is initiated by the operator depressing the actuating knob 198 at the end of the Bowden wire 196 in order to actuate the usual clutch-operating mechanism between the driving motor 180 70 and the phonograph proper.

Of course, with the system described with respect to Fig. 1 of the drawings, it is possible for any branch station to converse with the main or operator's station and also to be acoustically 75

coupled to the subscriber's outside telephone system.

Referring now to Fig. 4 of the drawings, a modified and improved system embodying my invention is illustrated diagrammatically, in which any branch station may converse with the operator's station and also may be acoustically coupled to the subscriber's outside telephone.

This modified system is generally analogous to many respects to the system already described but embodies certain improved features. For instance, in addition to means for automatically energizing the electronic amplifier as soon as the French telephone instrument is removed from its cradle, my modified system also includes an auxiliary battery-operated transmitter associated with my acoustical coupling device, so that immediate communication with a branch station may be established before the amplifier reaches a proper operating condition. Also with this arrangement, it is unnecessary to energize the amplifier at all for inter-office communication.

Another operating feature is a simplified arrangement of the independently operable transmitting and receiving circuits which utilize a common return instead of comprising two separate two-wire circuits, thus enabling the use of control switches of more simple construction at the branch stations, with correspondingly simpler circuit connections, while still permitting independent control of the respective circuits.

A further feature is an automatic lock-out end signal system whereby whenever one of the branch stations is in operation it is impossible for any other branch station to cut in or be operably connected to the system. Other improvements will also be apparent as the description proceeds.

This modification of my invention also includes a buzzer and annunciator signal system of the so-called "auto-call" type, whereby any branch station may signal the operator and register an indication of such signal by means of an annunciator in the event that the operator is temporarily absent, and whereby the operator may selectively signal any branch station and through an annunciator located at each station indicate that such a call has been made in the event no one is present to answer the signal.

In the system of Fig. 4, there is shown an operator's station O' and branch stations A', B', C'. At the operator's station is a subscriber's outside telephone set T' having a French phone F' of the usual type and this subscriber's telephone set rests upon a sub-base (not shown) similar to that illustrated in Fig. 1, which is also provided with relatively movable spring contacts 20' and 24' which are adapted to make cooperative electrical engagement when the telephone instrument F' is removed from its cradle. In Fig. 4, however, the engagement of the spring contacts 20' and 24' is utilized to connect a suitable electronic amplifier 90' with the source of energy, marked Power, as soon as the telephone instrument F' is removed from its cradle and, at the same time, a visible signal 36' is brought into action. A timing device, such as set forth in connection with Fig. 1, may also be employed, if desired. The power circuit of the amplifier 90', which is thus established, includes conductor 214, spring contacts 20' and 24', and conductor 276, while the other power connection to the amplifier comprises conductor 278. The signal device 36' is simultaneously connected across

the source of power by means of conductor 280.

By immediately energizing the amplifier 90' when the telephone instrument F' is removed from its cradle, the amplifier tubes are quickly subjected to heat and reach a suitable condition of operation before being called upon to function in the system.

Also located at the operator's station O' is an acoustical coupling and control device C' of which the amplifier 90' constitutes a part and which is generally similar to that described in connection with Fig. 1. This coupling device is shown only diagrammatically but it will be understood that it is of the same general construction as that already described and includes a similar microphone 60', a loud-speaker 62', a control switch 70', a switch-actuating rod 66', batteries 126' and 284, a signal device or buzzer 120', an electromagnetically operated switch 124', and an auxiliary transmitter or microphone 288.

The control switch 70' comprises a plurality of spring contacts 290, 292, 294, 296 and 298 which are mounted on an insulating block 300 in such manner that spring contacts 294 and 296 are normally in engagement, while the other spring contacts 290, 292, and 298 are out of engagement and are, therefore, electrically inoperative. Spring contact 292 carries at its extended free end a button 302 of insulating material which is adapted to engage the extended free end of spring contact 296. When the switch actuating rod 66' is pushed in, engagement is effected between spring contacts 290 and 292, while the electrical connection between spring contacts 294 and 296 is interrupted and, at the same time, an electrical engagement of spring contacts 296 and 298 is established.

The various branch stations A', B', C' are similar in construction and a description of branch station A' will be sufficient. At branch station A' is a telephone set which is shown for illustrative purposes as of the wall type, and which includes a transmitter 132' and a receiver 134' which normally hangs on a hook lever 138' pivoted at 140' and held downwardly against a stop 142' by the weight of the receiver 134' when it is hung upon the hook lever. A spring 144' cooperates with a downwardly extending arm 304 of the hook lever to raise the hook lever whenever the receiver is removed therefrom. The hook lever 138' is also provided with an insulating finger 146' disposed beneath a control switch 139' comprising a spring contact 306 and a plurality of cooperating spring contacts 308, 310 and 312, all of which are mounted on an insulating block 314. When the receiver 134' is in position on the hook lever 138', the spring contacts are out of engagement, but when the receiver is removed therefrom, the spring 144' raises the hook lever to cause the insulating finger 146' to engage the spring contact 306 and press it upwardly into electrical engagement with the spring contacts 308, 310 and 312.

For the purpose of preventing the operation of other branch stations when one of the branch stations is being utilized, each of the hook levers 138' is provided with an upwardly extending segment 316 having a notch 318 therein into which a locking finger 320 of a pivotally mounted latch 322 may be positioned under certain circumstances in order to lock the hook lever against being raised, in the event that the receiver 134' is removed therefrom. This pivotally mounted latch 322 constitutes the armature of an electromagnet 324 and is normally held in its upward

position against a stop by means of a spring 325. When the electromagnet is energized, the locking finger 320 of the armature 322 is pulled down into the notch 318 into locking engagement with the segment 316 to prevent the hook lever 138' from being raised, even though the receiver be removed therefrom.

Disposed above the armature-latch member 322 and in the path of movement thereof is a bell-crank lever 328 which is pivoted at 330, and its horizontal arm carries an adjustable weight 332, while the extremity of its vertical arm carries a signal disk 334. The bell-crank lever 328 constitutes a sort of semaphore signal and normally occupies a position such as shown in Fig. 4 with a depending finger 336 thereof resting upon the latch-armature 322. However, when the electromagnet 324 is energized, and its armature 322 is pulled down into locking position, the bell-crank 20 semaphore 328 rotates in a counterclockwise direction by reason of the weight 332 and moves the signal disk 334 into registry with an opening or window 338 in the casing (not shown) of the telephone wall set. If the disk 334 be painted red, for convenience, it will visibly indicate through the window 338 that the inter-office system is already "busy" or in use. Any party desiring to use the branch station will, therefore, wait until the system is "clear" or out of use. Of course, in lieu of a semaphore signal, any other suitable visible or audible buzzer signal may be employed.

For the purpose of enabling the operator to selectively signal any branch station and also for any branch station to signal the operator's station, a suitable buzzer or signal system S' of the so-called "auto-call" type is employed, and associated therewith are suitably located push buttons and annunciations, functioning in the usual manner to leave a visible indication of a call in the event that no one is present at the time the call is made. This buzzer or signal system S' is common in the art and will be understood without detailed description. The system includes a plurality of push buttons 170a, 170b and 170c which are conveniently located at the operator's station and which are adapted, when pressed, to complete suitable circuit connections to energize a plurality of combined annunciator and buzzer units 174a, 174b and 174c respectively located at the several branch stations A', B' and C'. On the other hand, the respective branch stations A', B' and C' are provided with conveniently located push buttons 340a, 340b and 340c, respectively, which are adapted to establish connections to annunciations 342a, 342b and 342c which are located at the operator's station, and which are operatively connected to a common buzzer 344.

Assuming the circuit connections to be as shown in Fig. 4, and that an outside call is received on the subscriber's telephone set T', the French telephone instrument F' is removed from its cradle by the operator and the call is answered. The decrease in weight of the telephone set T', by reason of the removal of the instrument F', causes the source of power marked Power to be immediately connected through switch members 20' and 24' to the amplifier 90', while at the same time the signal device 36' is operated, all in the manner previously described in detail.

By energizing the amplifier 90' immediately upon removing the telephone instrument F' from its cradle, the amplifier tubes are promptly subjected to heating current and are quickly brought to operative condition, so that the amplifier will

be in readiness for service by the time the desired party has been called to the proper branch station.

The operator having ascertained the party desired then depresses one of the push buttons, for instance, 170a, in the event that the desired party is located at station A', thereby signaling station A' by means of the combined buzzer and annunciator unit 174a. In responding to the signal, the party at station A' lifts the receiver 134' from its wall set and is at once enabled to talk with the operator through the transmitter 132', which, by reason of the operation of the control switch 139', is connected into circuit with battery 126' and the loud speaker 62' associated with the coupling device C' at the operator's station. This transmitting circuit is established automatically as the receiver 134' is removed from its hook lever, inasmuch as the spring 144' then operates in the manner already described to close the respective spring contacts of the control switch 139', as will be understood. The transmitting circuit thus established includes battery 126', conductors 346, 348, loud-speaker 62', conductors 350, 352, transmitter 132', conductor 354, spring contacts 308, 306, and 310 of control switch 139' associated with branch station A', and thence through conductor 356 and conductor 358 to the other side of the battery.

Simultaneously, an operatively independent receiving circuit, including the transmitter 288 at the operator's station and the receiver 134' at station A', is established. This circuit includes battery 126', conductor 346, conductor 360, transmitter 288, conductor 362 and spring contacts 294 and 296 of control switch 70' associated with the acoustical coupling device C', which contacts are the only ones of said control switch which are normally in engagement, the circuit being completed through conductor 364, conductor 366, receiver 134' at station A', conductor 368, spring contacts 306 and 310 of control switch 139', and thence back to the battery through conductors 356 and 358.

Upon the completion of the local or inter-office transmitting and receiving circuits just recited, the party at branch station A' and the operator may converse as desired, during which the party at station A' will be advised of the call and in turn will advise the operator that he is ready to receive it.

Before proceeding with an explanation of effecting the acoustical connection with the subscribers' telephone instrument F', it is important to understand certain control features of my invention which are initiated at the time the receiver 134' at station A' is removed from its hook lever. This feature has to do with automatic "lock out" arrangement, by means of which all of the other branch stations are definitely latched in such a manner as to prevent their use while station A' is being used.

To accomplish this result the circuit arrangements are such that when the control switch 139' associated with branch station A' is actuated into its closed position, upon the removal of the receiver 134', a circuit is established from battery 126' which includes the electromagnets 324 of all of the branch stations. This circuit also includes the electromagnet of control switch 124' at the operator's station. The circuit by which this is effected includes battery 126', conductor 346, conductor 370, conductor 372, auxiliary battery 284, electromagnet 314 of the electromagnetically operated switch 124', conductor 376, electro-magnet 75

324, associated with the telephone set at station C', conductor 378, electromagnet 324 at station B', conductor 380, electromagnet 324 at station A', conductor 382, conductor 384, spring contacts 5 312, 386 and 310 of control switch 139' at station A', and thence through conductors 356 and 358 to the battery 126'.

By thus energizing the electro-magnets 324 of the respective branch stations A', B' and C' a 10 downward pull is exerted upon all of their associated latch-armatures 322, all of which, except that at station A', are pulled downwardly against the action of the springs 326, whereby the locking fingers 328 thereof are positioned in the notches 15 318 of the respective segments 316, in locking engagement therewith, to thereby positively prevent the upward movement of the respective hook levers 138' in the event that the receivers 134 of said stations should be removed therefrom. Of course, the latching armature 322 of station A' is prevented from being pulled downwardly into the notch 318 associated with the segment 316 of its hook lever 138' by reason of the fact that upon the initial removal of the receiver 134' 20 therefrom, the hook lever was raised and the associated segment 316 rotated clockwise beneath the end of the latching finger 328 so that even though the electromagnet 324 at station A' be energized, it is impossible for its latch-armature 322 to be moved.

However, the other branch stations B' and C' are locked against use as already described, and, moreover, the semaphore signal devices of these other branch stations will operate, as already set 35 forth, to visibly indicate at the openings or windows 338 of the respective wall sets that the system is "busy" for the time being. Therefore, any party at these stations, noting that the "busy" signal is set, will refrain from attempting to utilize the system until this visible signal indicates that the system is "clear" and ready for use.

At the same time that the automatic locking feature just described is rendered operative, the electromagnet 374 of control switch 124' at the 40 operator's station is also energized, and this magnet attracts its armature 386 against the action of spring 388, thereby disengaging the cooperating contacts 390 of the electro-magnetically operated switch 124', which contacts are in circuit with the 45 warning buzzer 128'. Thereby, the buzzer circuit is opened and the buzzer prevented from operating for the time being.

Reverting now to the acoustical coupling of the 50 inter-office system with the outside system, after the party at station A' has indicated that he is ready to receive the outside call, the operator then depresses the actuating rod 66' of the acoustical coupling device C' to actuate the control switch 70' and places the French telephone instrument 60 F' in position upon said coupling device in the manner described in connection with Fig. 1, whereby the receiver 8' is in registry with and in acoustical relation to the microphone 60', while the transmitter 10' occupies a position in registry 65 with and in acoustical relation to the loud speaker 62'.

In so actuating the control switch 70', the 70 normal engagement of spring contacts 294 and 296 is broken, while establishing engagement between spring contacts 290 and 292 and the spring contacts 296 and 298, as will be understood.

The interruption of the circuit through the transmitter 288 by reason of the disengagement of spring contacts 294 and 296 renders this transmitter and its receiving circuit, hereinbefore de-

scribed, inoperative. However, by this time, the amplifier 90', which was connected to the source of power when the telephone instrument F' was first removed from its cradle, will have now become heated up to full operative condition and 5 ready for use.

Concurrent with the interruption of the receiving circuit through the transmitter 288, another receiving circuit is set up from the output side of the amplifier 90' which includes conductor 392, 10 spring contacts 298 and 296 of control switch 70', conductor 384, conductor 386, receiver 134' at the station A', conductor 368, spring contacts 306 and 310 of control switch 139' and thence through conductors 356, 358 and conductor 394 to the other 15 side of the output circuit of the amplifier 90'. This receiving circuit is operatively independent of the transmitting circuit previously described, although these two operative circuits include a common return circuit. The arrangement however, is such that both circuits are independently controllable. The utilization of a common circuit for both of the independently operable and independently controllable transmitting and receiving circuits materially simplifies the circuit 20 connections and permits a correspondingly simpler construction of the control switches 70' and 139'.

Having effected an acoustical coupling between the subscribers' telephone instrument F' of the 30 outside system and the inter-office system by means of the acoustical coupling device C' in the manner described, and having established the independently operable transmitting and receiving circuits, as above set forth, the conversation 35 between the calling party on the outside system and the called party at station A' may be carried on in the usual manner.

During the conversation the visible signal 38' at the operator's station O' continuously indicates 40 that the conversation is in progress. Also, by reason of the "lock-out" arrangement, previously described, it is impossible for any of the other branch stations B' and C' to interfere with or break into the conversation. Moreover, the 45 semaphore signal devices associated with the branch stations B' and C' visibly indicate that the system is in use and is not available at these branch stations, until such time as the conversation in progress has terminated.

Before describing the operation of the system after the conversation has been terminated, it is important to understand certain preparatory or intermediate functions of my system which are carried out at the time that the control switch 70' 55 of the coupling device C' is actuated by the operator through the actuating rod 66'. This has to do with preliminarily setting up suitable signal circuits which will later become operative when the receiver at the branch station A' is hung up 60 at the conclusion of the conversation, and at which time the buzzer 128' will operate to warn the operator that as the conversation has terminated, the French telephone instrument F' should be restored to its cradle on the public 65 telephone set.

In connection with this control feature it has already been explained that upon the removal of the receiver 134' at station A', electromagnet 374 of the electro-magnetically operated switch 70 124' in the acoustical coupling device C' is energized to attract its armature 386 and thus separate the cooperating contact members 390 to thereby open a circuit including the buzzer 286. However, when the control switch 70' is actuated 75

5 by the operator, preparatory to effecting the acoustical connection between the inter-office and the outside systems, contact members 290 and 292 are brought into engagement, and one side of the battery 126' is connected through conductor 346, conductor 370, conductor 396, spring contacts 290 and 292 and conductor 398 to the buzzer 386 and thence through conductor 400 to armature 386 and its associated contact 390 of the 10 electromagnetically operated switch 124'. This switch, being now in open position, by reason of the energization of electromagnet 374, as already explained, prevents the operation of the buzzer 120', although the other cooperative switch member 390 is connected by conductor 402 and conductor 358 with the other side of the battery.

15 The circuit of the warning buzzer 120' at the operator's station O' is thus placed in condition for the operation as soon as the conversation has been completed and the receiver 134' at station A' has been restored to its hook lever 138'. When this is done, the weight of the receiver 134' moves hook lever 138' at station A' to its downward position in opposition to the spring 144'. Thereby, the control switch 139', associated with station A', is permitted to resume its normal open position, whereupon the receiving circuit and the transmitting circuit, together with the energizing circuit of the lock-out electromagnets 324, 20 are interrupted, and by reason thereof all of said electro-magnets deenergized. This permits the latch-armatures 322 at branch stations B' and C' to be retracted by their springs 326 out of locking engagement with the notched segments 316 of their associated hook levers. In this manner the telephone wall sets at branch stations B' and C' are released from their locked inoperative positions and restored to their normal condition 25 in readiness for subsequent use.

30 40 Of course, the telephone wall set at station A' is also ready for use, in view of the disengagement of segment 316 of its hook lever 138', which was effected at the time that the receiver 134' was again restored to said hook lever. Contemporary 45 with the restoration of the several branch stations A', B' and C' to normal position, the associated semaphore signal disks 334 of stations B' and C' are returned to their "clear" positions, as indicated in Fig. 4, by reason of the springs 326, 50 through the agency of the latch-armatures 322 and the weighted bell crank levers 328, upon which the signal disks 334 are mounted.

55 The warning buzzer 120' at the operator's station O' is rendered operative when the control switch 139' of branch station A' is opened upon the restoration of the receiver 134' to its hook lever, in view of the fact that the opening of the control circuit through the electromagnets 324 of the several branch stations also deenergizes 60 electromagnet 374 of the electromagnetically operated switch 124' which is located in the acoustical coupling device C' at the operator's station. As soon as this electromagnet is deenergized its armature 386, which carries one of the 65 cooperating contacts 390, is actuated by spring 388 to the position shown in the drawings in which the energizing circuit through the buzzer 286 and contacts 390 is closed.

70 Thereupon, the buzzer 120' becomes operative to give a warning signal to the operator that the conversation has terminated and the receiver 134' at station A' had been hung up. This buzzer signal continues in operation until the French telephone instrument F' is moved from acoustical 75 relation with the acoustical coupling device C'

and the control switch 70' restored to its initial condition of operation by the operator pulling out the actuating rod 66' to thereby reestablish the initial circuit conditions under which the inter-office telephone system is again rendered operative for inter-office communication or for further communication with the outside system in the manner already described. 5

10 Of course, after the operator has pulled out the switch actuating rod 66' of the acoustical coupling device C', the energizing circuit of the buzzer 120' is interrupted by the separation of the spring contacts 290 and 292 of the control switch 70', whereupon the buzzer ceases to function. The operator then restores the French 15 telephone instrument F' to its normal position upon the cradle of the main subscribers' telephone set T'.

20 Thereupon, the added weight of the instrument F' depresses the floating platform of the sub-base (shown in Fig. 1), and effects a disengagement of the spring contacts 20' and 24' whereby the amplifier 90' is cut off from the source of power. At the same time visible signal device 36' 25 also becomes inoperative.

25 The combined inter-outer telephone system is then in readiness for further use, either in inter-office communication or communication by means of an acoustical connection with the outside system. 30

35 While I have described in detail the operation of my improved inter-outer telephone system, as illustrated in Figs. 1 and 4, in connection with receiving a call from the outside system for a party at one of the branch stations of the inter-office system, it will be understood without further explanation that the call may originate from any of the inter-office branch stations. Moreover, the operator may at any time call any of the branch stations and any of the branch 40 stations may call the operator. 40

45 Referring now to Fig. 5 of the drawings, I have illustrated diagrammatically a modification of my invention which may be utilized in connection with inter-outer telephone systems of various types, including those described with respect to Fig. 1 and Fig. 4, and which embodies a direct current battery-operated electronic amplifier in lieu of an alternating current type of amplifier 50 previously referred to. 50

55 Direct current battery-operated amplifiers are known in the art, and are generally similar in construction and operation to alternating current amplifiers, with the exception that they include a so-called "A" battery, a "B" battery and a "C" battery for supplying the necessary energy instead of being connected to a source of alternating or direct current energy. The A battery supplies the energy for heating up the vacuum tubes of the amplifier to bring them to operative 60 condition, and B and C batteries automatically become operative to perform their usual functions when the resistance of the vacuum tubes is overcome through suitable heating thereof by the "A" battery. 65

70 With such a battery operated type of electronic amplifier, it is particularly important to utilize a minimum of energy from the auxiliary A, B and C batteries and, therefore, the amplifier should be energized only when actually in use. The feature of my invention involving the immediate and automatic energization of the amplifier upon removing the French telephone instrument from the cradle of the subscribers' telephone set, is therefore of prime importance when 75

a direct current battery-operated amplifier is employed.

Furthermore, it is desirable to avoid unnecessary drain upon the A battery, and I therefore 5 arrange to utilize the usual alternating or direct current source of energy for signal and other control purposes, and restrict the A battery as far as possible to merely supply the energizing current for the amplifier.

10 Referring specifically to Fig. 5, a regulatable direct current amplifier 90², constituting a part of my acoustical coupling device C², is provided with an A battery 406 for supplying the energizing current to preliminarily heat the amplifying 15 fier up to operating condition, and a B battery 408 and a C battery 410, operating in the usual manner which need not be described. The A battery 406 is connected to the amplifier 90² by means of an electromagnetically operated relay 20 or switch 412 which embodies an electromagnet 414 and a pivotally mounted armature switch arm 416 carrying an electrical contact 418, which cooperates with a stationary contact 420 in the usual manner. The armature 416 is normally 25 held in open position by a spring 422. However, when the control circuit from the source of energy marked Power is completed through contacts 20² and 24², by the removal of the French telephone instrument F² from the cradle of the 30 subscriber's telephone set T², in the manner previously set forth, the electromagnet 414 is energized and draws its armature 416 into position to effect a cooperative engagement between the contacts 418 and 420. In this way an energizing 35 circuit for the amplifier 90² is completed from one side of the A battery 406, through conductor 424, cooperating contacts 420 and 418 of the electromagnetically operated switch 412, and thence 40 through the armature switch arm 416 and conductor 426 to one terminal 428 of the amplifier, the other terminal 428 of which is already connected by conductor 430 to the other side of the A battery 406.

The direct current battery-operated amplifier 45 90² is thereby connected to its A battery 406 as soon as the French telephone instrument is removed from its cradle, and the warming-up period of the amplifier tubes is thus promptly initiated.

50 Of course, at the same time that the French telephone instrument is picked up and cooperative engagement of contacts 20² and 24² is established, a suitable signal device 36² and a timing device 42² are also connected across the source of power and become operative, as will be readily understood from the previous description. These auxiliary devices, as well as the electro-magnetically operated switch or relay 412, are preferably 55 connected to the usual power source in order to relieve the A battery 406 of unnecessary service.

Without further description, it will be understood that aside from the modified operation just set forth, the inter-outer telephone system of my invention operates in the manner previously 60 explained, whereby an outside telephone call may be received acoustically by a party at any branch station. Obviously, when the conversation has terminated and the French telephone instrument has been restored to its cradle, the contacts 20² and 24² are disengaged and the power cut off from the signal device 36², the timing device 42² and the electromagnet 414 of the relay switch 412. Thus, the energizing circuit 65 of the amplifier 90² is interrupted by the separation of contacts 418 and 420, and the A

battery 406 is thus disconnected from service. Subsequently, the B battery 408 and C battery 410 automatically become inoperative as soon as the amplifier tubes cool down.

Although I have shown and described my invention as embodying more or less specific construction and arrangements of parts and circuit connections, as well as steps of operation, it should be understood that many modifications may be made therein without departing from the spirit and scope of my invention. Therefore, only such limitations should be imposed as are indicated in the appended claims.

I claim:

1. In a telephone system, the combination of 15 a subscriber's telephone set including a supporting base and a removable telephone instrument normally resting thereon, an electronic amplifier, means for acoustically coupling said instrument to said amplifier and means upon which the telephone set is adapted to rest and operatively dependent upon the weight thereof for automatically energizing said amplifier when the telephone instrument is removed from its supporting base.

2. In a telephone system, the combination of 25 a subscriber's telephone set including a supporting base and a removable telephone instrument normally resting thereon, a timing device of the electric clock type for progressively indicating the passage of time and means upon which the 30 telephone set is adapted to rest and operatively dependent upon the weight thereof for automatically initiating the operation of said timing device when the telephone instrument is removed from its supporting base for purposes of 35 telephonic communication to progressively indicate the length of time of said telephonic communication.

3. A system of telephonic communication comprising in combination a public telephone system 40 including a telephone set having a supporting base and a removable telephone instrument normally resting thereon, an electrically independent inter-office telephone system including an electronic amplifier for amplifying messages received 45 acoustically by the inter-office system, means for effecting an acoustical coupling between said inter-office telephone system and public telephone system and means associated with said public telephone set for automatically energizing said 50 amplifier upon removing said telephone instrument from its supporting base.

4. A system of telephonic communication comprising in combination a public telephone system including a telephone set having a supporting base and a removable telephone instrument normally resting thereon, an electrically independent inter-office telephone system, an electronic amplifier for amplifying messages received 55 acoustically by the inter-office system, means for effecting an acoustical coupling between said public and said inter-office telephone systems, a sub-base including a spring-supported floating platform upon which the public telephone set is adapted to rest, and means including a plurality of relatively movable electrical contacts operatively associated with said floating platform and adapted for electrical engagement when the telephone instrument is removed from its base for automatically connecting the amplifier to a 60 source of power.

5. A system of telephonic communication comprising in combination a public telephone system including a telephone set having a supporting base and a removable telephone instrument nor- 75

5 mally resting thereon, an electrically independent inter-office telephone system including a battery-operated electronic amplifier including an A battery for heating the amplifier to operative condition, means for effecting an acoustical coupling between said public telephone system and said inter-office telephone system, and means associated with the public telephone set for automatically connecting the A battery to the electronic amplifier upon the removal of the telephone instrument from its supporting base.

10 6. A system of telephonic communication comprising in combination a public telephone system including a telephone set having a supporting base and a removable telephone instrument normally resting thereon, an electrically independent inter-office telephone system, a battery-operated electronic amplifier including an A battery for heating the amplifier to operative condition, means for effecting an acoustical coupling between said public and said inter-office telephone systems, and means associated with the public telephone set and including an electromagnetically operated relay switch for automatically 15 connecting the A battery to the electronic amplifier upon the removal of the telephone instrument from its supporting base.

20 7. A system of telephonic communication comprising in combination a public telephone system including a telephone set having a supporting base and a removable telephone instrument normally resting thereon, an electrically independent inter-office telephone system, means for effecting an acoustical coupling between said public and said 25 inter-office telephone systems, a timing device of the electric clock type and means associated with said public telephone set and dependent upon the weight thereof for initiating the operation of said timing device upon the removal of the telephone 30 instrument from its supporting base.

35 8. A system of telephonic communication comprising in combination a public telephone system including a telephone set having a supporting base and a removable telephone instrument normally 40 resting thereon, an electrically independent inter-office telephone system, means for effecting an acoustical coupling between said public and said inter-office telephone systems, a timing device of the electric clock type, a spring-supported floating platform upon which the telephone set is 45 adapted to rest and electrical means operatively associated with said floating platform for initiating the operation of said timing device upon the removal of the telephone instrument from its sup- 50 porting base.

55 9. A system of telephonic communication comprising in combination, a public telephone system including a telephone instrument, an inter-office telephone system comprising independently operable transmitting and receiving circuits, said transmitting circuit including a transmitter at a branch station and a loud-speaker at an operator's station, and said receiving circuit including a receiver at said branch station and a transmitter 60 at said operator's station, an electronic amplifier in one of said circuits, switching means located at said branch station and normally held in inoperative open position by the weight of said receiver at the branch station but actuated into 65 operative closed position when said receiver is picked up for conversation to connect said transmitting and said receiving circuits into operative relation, and means for effecting an acoustical coupling between said telephone instrument and 70 said inter-office telephone system.

75 10. A system of telephonic communication comprising in combination a public telephone system having a telephone instrument, an inter-office telephone system having operably independent transmitting and receiving circuits adapted to be set up between an operator's station and a branch station, said transmitting circuit including a transmitter at the branch station and a loud-speaker at the operator's station, and said receiving circuit including a receiver at said branch station, a transmitter and an amplifier at said operator's station, switching means located at the branch station and normally held in inoperative open position by the weight of the receiver at the branch station, but actuated into operative closed position when the receiver is picked up, for connecting said transmitting and receiving circuits into independent operative relation, and means located at the operator's station for effecting an acoustical coupling between said public telephone instrument and said inter-office system.

80 11. A system of telephonic communication comprising in combination a public telephone system having a telephone instrument, an inter-office telephone system having operably independent transmitting and receiving circuits adapted to be set up between an operator's station and a branch station, said transmitting circuit including a transmitter at the branch station and a loud-speaker at the operator's station, and said receiving circuit including a receiver at said branch station, a transmitter and an amplifier at said operator's station, switching means located at the branch station and normally held in inoperative open position by the weight of the receiver at the branch station but actuated into operative closed position when the receiver is picked up for connecting said transmitting and receiving circuits into independent operative relation, means located at the operator's station for effecting an acoustical coupling between said public telephone instrument and said inter-office system, a signal device at the operator's station having a normally open energizing circuit during an outside telephone conversation, and control means including a circuit through said branch station switching means adapted to be rendered operable only when the outside telephone conversation has terminated and the branch station receiver is restored to its normal inoperative position to effect the completion of said signal energizing circuit and operate said signal device.

85 12. A system of telephonic communication comprising in combination a public telephone system having a telephone instrument, an inter-office telephone system having operably independent transmitting and receiving circuits adapted to be set up between an operator's station and a branch station, means located at said operator's station for effecting an acoustical coupling between said public telephone instrument and said inter-office system, and automatic means for signaling the operator at said operator's station while the acoustical coupling means at the operator's station is still in operative position and when the receiver at said branch station is hung up after the telephone conversation has been terminated.

90 13. A system of telephonic communication comprising in combination a public telephone system having a telephone instrument, an inter-office telephone system having operably independent transmitting and receiving circuits adapted to be set up between an operator's station

- and a branch station, an acoustical coupling device at said operator's station adapted to receive and support the public telephone instrument in efficient acoustical relation with the operably 5 independent transmitting and receiving circuits of said inter-office system, a switching device at said operator's station arranged to be actuated by the operator into operative position when the public telephone instrument is placed in acoustical 10 relation with said coupling device, a switching device at said branch station biased to its operative closed position but held in inoperative open position by the weight of the branch station receiver when hung up, a signal device at said operator's station and control means cooperatively associated with both of said switching devices and said signal device for effecting the operation of said signal device while said coupling device is in operative position and when said branch 15 station receiver is hung up after the termination of a telephone conversation.
14. A system of telephonic communication comprising in combination a public telephone system including a telephone instrument, an inter-office 20 telephone system comprising a two-wire one-way receiving circuit including a receiver at a branch station and a transmitter and an amplifier at an operator's station, a separate and independent two-wire one-way transmitting circuit including a transmitter at the branch station and a receiver at the operator's station, and a switching device at the branch station normally held in inoperative open position by the weight of the receiver at said station but actuated into operative closed position when relieved of the weight of the receiver, said switching device being arranged in said separate two-wire one-way transmitting and receiving circuits to automatically effect the establishment of said circuits when 25 the branch station receiver is picked up for use, and means for effecting an acoustical coupling between said telephone instrument and said inter-office system.
15. A system of telephonic communication, comprising in combination a public telephone system including a telephone instrument, an inter-office telephone system comprising operably independent transmitting and receiving circuits including a three-wire circuit, one of which is a 30 common return for both the transmitting and the receiving circuits, the receiving circuit including a receiver at a branch station and an amplifier and a transmitter at the operator's station, the transmitting circuit including a transmitter at the branch station and a receiver at the operator's station, a battery included in the common return of said transmitting and receiving circuits, and a switching device at the branch station for establishing said transmitting and receiving circuits when the receiver at the branch station is picked up for use, said switching device being held in inoperative open position by the weight of the receiver when not in use.
16. An inter-office telephone system comprising a transmitting circuit including a transmitter at a receiving station and a receiver at an operator's station, a receiving circuit including a receiver at the branch station and a transmitter at the operator's station, a phonographic sound-recording device controllable at the operator's station and including a loud-speaker operatively associated with said recording device, means including circuit connections and a switching device at the operator's station for operatively connecting the transmitter at the operator's station 35 with either the receiver at the branch station or the loud-speaker associated with said sound-recording device whereby a message can be received at the branch station or be recorded on the sound-recording device, and means for acoustically picking up such message from the loud-speaker associated with said sound-recording device and transmitting it to the receiver at the branch station while the message is being recorded by the sound-recording device. 40
17. A system for recording telephonic messages comprising a phonographic sound-recording device, a loud-speaker acoustically associated therewith, a transmitter constituting a part of a transmitting circuit including said loud-speaker, means for controlling the operation of said sound-recording device to record messages originating in said transmitter and delivered to said loud-speaker, a pick-up microphone located adjacent and in acoustical relation with said loud-speaker, 45 and a transmitting circuit associated with said pick-up microphone for transmitting the message acoustically received thereby to a receiver at a distant point. 50
18. An inter-office telephone system for inter-connecting a plurality of branch stations with a main or operator's station, comprising a transmitter and a receiver at the operator's station and each of the branch stations, means including a switching device at each of the branch stations 55 for establishing independently operable receiving and transmitting circuits between the operator's station and the branch stations, said switching means at the branch stations being normally held in inoperative open position by the weight of the 60 respective receivers at said stations but actuated into operative closed positions when the receivers are picked up for use, a plurality of series-connected electromagnetically operated latching devices located at the respective branch stations and adapted to be actuated into locking engagement with the respective switching devices at said branch stations when the receiver at one of said branch stations is picked up for use, and means at the respective branch stations operatively associated with the respective electromagnetically operated latching means at said branch stations for indicating at all of said branch stations, except 65 the one in use, that the inter-office telephone system is being used. 70
19. An inter-office telephone system for inter-connecting a plurality of branch stations with a main or operator's station, comprising a transmitter and a receiver at the operator's station and each of the branch stations, means including a switching device at each of the branch stations 75 for establishing independently operable receiving and transmitting circuits between the operator's station and the branch stations, said switching means at the branch stations being normally held in inoperative open position by the weight of the respective receivers at said stations but actuated into operative closed positions when the receivers are picked up for use, and electromagnetically operated means rendered operative when the receiver at any of the branch stations is picked up for use for preventing the operation of the switching devices at all the other branch stations until the receiver in use is restored to its normal position. 80
20. An inter-office telephone system for inter-connecting a plurality of branch stations with a main or operator's station, comprising a transmitter and a receiver at the operator's station and each of the branch stations, means including a 85

switching device at each of the branch stations for establishing independently operable receiving and transmitting circuits between the operator's station and the branch stations, said switching 5 means at the branch stations being normally held in inoperative open position by the weight of the respective receivers at said stations, but actuated into operative closed positions when the receivers are picked up for use, and electromagnetically 10 operated means rendered operative when the receiver at one of the branch stations is picked up for use for signalling at all of the other branch stations to indicate that the system is in use.

21. A system of telephonic communication comprising a public telephone system including a telephone instrument, an inter-office telephone system electrically independent thereof and having a transmitting circuit including a transmitter at a branch station and a loud-speaker at the operator's station, an independently operable receiving circuit including a receiver at the branch station and a transmitter at the operator's station, a switching device at said branch station for setting up said transmitting and receiving circuits when 25 the receiver at said branch station is picked up for use, an acoustical coupling device at the operator's station including said loud-speaker, an auxiliary transmitter, and an amplifier in circuit therewith, for effecting an acoustical coupling between 30 the telephone instrument of the public telephone system and said inter-office system, and switching means at the operator's station adapted to be actuated when the acoustic coupling is effected for disconnecting the first-mentioned 35 transmitter at the operator's station from said receiving circuit while establishing a receiving circuit including the auxiliary transmitter and the amplifier at the operator's station and the receiver at the branch station.

40 22. In an acoustic coupling device for acoustically connecting a French telephone instrument of a public telephone system with a separate and independent inter-office telephone system, the combination of a cabinet having a vertically inclined panel provided with a pair of vertically disposed openings spaced to register with the fixedly spaced transmitter and receiver of the French telephone instrument, a microphone and a loud-speaker mounted within the cabinet immediately 45 behind the upper and lower panel openings respectively, a semi-circular outwardly projecting flange positioned immediately below the upper panel opening to receive the receiver end of the French telephone instrument and support said instrument in efficient acoustical relation with 50 said microphone and loud-speaker, a control switch mounted within the cabinet and a switch-actuating rod associated therewith and projecting outwardly through said panel intermediate said 55 panel openings with its outer end in position to engage the hand grip of the French telephone instrument and prevent it from being placed in efficient acoustical relation with said microphone and loud-speaker until said switch-actuating rod is depressed to effect the actuation of said control switch.

60 23. A system of telephonic communication, comprising in combination a public telephone system including a supporting base and a removable telephone instrument normally resting thereon, an electrically independent inter-office telephone system having an operator's station and a branch station adapted to be interconnected by independently operable receiving and 65 transmitting telephone circuits, each circuit in-

cluding a telephone receiver and a telephone transmitter, both the public and the independent inter-office systems being normally capable of independent conventional use but also adapted to be interconnected acoustically when the operator 5 manually places the telephone instrument of the public telephone system in acoustical relation with the receiver and the transmitter located at the operator's station of the inter-office system, and switching means located at the branch station 10 of the inter-office system and normally held in inoperative position for establishing the independently operable transmitting and receiving circuits when the receiver at said branch station is picked up for use. 15

24. A system of telephonic communication comprising in combination a public telephone system having a telephone instrument, an inter-office telephone system having operably independent transmitting and receiving circuits 20 adapted to be set up between an operator's station and a branch station, said transmitting circuit including a transmitter at the branch station and a loud-speaker at the operator's station, and said receiving circuit including a receiver at said branch station, a transmitter and an amplifier at said operator's station, switching means located at the branch station and normally held in inoperative open position by the weight 25 of the receiver at the branch station but actuated into operative closed position when the receiver is picked up for connecting said transmitting and receiving circuits into independent operative relation, means located at the operator's station for effecting an acoustical coupling between said 30 public telephone instrument and said inter-office system, and signal means at the operator's station and controllable by the switching means at said branch station for warning the operator 35 when the receiver at the branch station has been restored to its normal inoperative position after an inter-outer telephone connection has been interrupted at said branch station. 40

25. A system of telephonic communication comprising in combination, a telephone system 45 having a loud-speaker adapted to receive telephonic messages, a phonographic sound-recording device with which said loud-speaker is acoustically associated for recording the telephonic messages received by said loud-speaker, means 50 disposed in acoustical relation to said loud-speaker for picking up the telephonic messages from said loud-speaker and relaying them to a distant telephone receiver while said messages are being recorded. 55

26. An inter-office telephone system adapted to interconnect a plurality of branch stations with a main or operator's station, means at each branch station for establishing telephone connections between such branch station and the operator's station and automatic means interlocking all of said branch stations for preventing the operation of all but one of said branch stations when said one of said branch stations is in use. 65

27. An inter-office telephone system adapted to interconnect a plurality of branch stations with a main or operator's station, means at each branch station for establishing telephone connections between such branch station and the operator's station and automatic means interlocking all of said branch stations for effecting a signal at all but one of said branch stations when said one of said branch stations is in use. 70

28. An inter-office telephone system adapted to 75

- interconnect a plurality of branch stations with a main or operator's station, means at each branch station for establishing telephone connections between such branch station and the operator's station and automatic means interlocking all of said branch stations for preventing the operation of and effecting a signal at all but one of said branch stations when said one of said branch stations is in use.
- 10 29. In an acoustical coupling device for acoustically connecting a French telephone instrument of a public telephone system with a separate and electrically independent inter-office telephone system, the combination of a cabinet having a 15 vertically inclined panel provided with a pair of vertically disposed openings spaced to register with the fixedly spaced transmitter and receiver

of the French telephone instrument, a microphone and a loud-speaker mounted within the cabinet in operative proximity to said upper and lower panel openings, means associated with said cabinet to receive and support the French telephone instrument with its transmitter and receiver in efficient acoustical relation to said loud-speaker and said microphone, a control switch mounted within the cabinet and switch-actuating mechanism therefor so disposed as to prevent the French telephone instrument from being placed in efficient acoustical position on said inclined panel until said switch-actuating mechanism is actuated to effect the operation of said control switch.

RICHARD VARLEY.
